UNITED STATES PATENT OFFICE.

DAVID ROBINSON, OF PAWTUCKET, RHODE ISLAND, ASSIGNOR TO DRAPER COMPANY, OF HOPEDALE, MASSACHUSETTS, A CORPORATION OF MAINE.

MULTIPLE-HARNESS LOOM.

SPECIFICATION forming part of Letters Patent No. 743,333, dated November 3, 1903.

Application filed May 27, 1903. Serial No. 158,917. (No model.)

To all whom it may concern:-

Be it known that I, DAVID ROBINSON, a subject of the King of Great Britain, and a resident of Pawtucket, county of Providence, State of Rhode Island, have invented an Improvement in Multiple-Harness Looms, of which the following description, in connection with the accompanying drawings, is a specification, like characters on the drawings representing like parts.

In a multiple-harness loom—that is, a loom in which the shedding cycle comprises three or more picks—if the filling fails and the loom turns over a few picks without laying filling in the shed it is necessary for the weaver to turn the loom either backward or forward until the pick of the cycle is found in which the last filling was laid in order to match the pick. The new filling or the continued laying of filling is then started from the point where the filling was previously laid and terminated. This of course is important only when a matched pick and an unbroken pattern in the weave is required, and it will be manifest that the greater the number of harnesses or, what is equivalent, the greater the number of picks in the shedding cycle, the more will the loom have to be turned over when it is necessary to find the pick in which the filling was last laid. In a feeler-loom wherein fresh filling is provided automatically upon substantial exhaustion of the running filling—*i. e.*, the filling which is being laid by the shuttle—the loom is very apt to turn over a few picks before its stoppage due to filling failure. Such filling failure may be breakage of the filling or a failure of the filling to be properly laid after filling replenishment.

When it is desired to find or match the pick in a multiple-harness loom, the usual practice is to take the shuttle out of the shuttle-box and turn the loom over by hand until the desired pick is found, care being taken by the weaver to prevent the dagger of the protector mechanism from striking the frog. If the loom be also provided with filling-replenishing mechanism and a controlling-filling-feeler, care must also be taken to prevent the feeler from causing the operation of the filling-replenishing mechanism, because as

there is no shuttle in use the feeler will act as it would upon substantial exhaustion of the running filling.

The present invention has for its object the production of means for greatly facilitating the finding or matching of a pick in a multiple-harness loom, and as will appear hereinafter it is equally adapted to a non-replenishing loom or a replenishing feeler-loom, wherein the shedding cycle comprises three or more picks and it is requisite to match the pick. In accordance therewith the invention comprehends means manually controlled and movable into position to prevent or arrest the operation of the protector mechanism and also to prevent the operation of replenishing mechanism in a loom so equipped. The shuttle is then removed, and the weaver can run the loom without hindrance for as many picks as may be necessary by holding on the shipper, and when the desired pick is found the loom is stopped and the shuttle inserted. Insertion of the shuttle releases the parts from the control of said manually-controlled means, and the latter is returned automatically to normal position, leaving the loom in condition to be started for continued operation. By thus running the loom with no shuttle in either box it is necessary to arrest the taking up of the cloth while no filling is being laid in the shed, and means for accomplishing this result are herein provided.

The various novel features of the invention will be set forth hereinafter in the specification describing one practical embodiment thereof, and such novel features will be particularly pointed out in the following claims.

Figure 1 is a left-hand side elevation of a portion of a multiple-harness loom embodying one practical embodiment of the invention, the loom being shown as equipped with automatic filling-replenishing mechanism and a controlling filling-feeler. Fig. 2 is a plan view of the left-hand portion of the loom, showing the feeler mechanism and the means in inoperative position for preventing the operation of the protector and filling-replenishing mechanisms. Fig. 3 is a similar view omitting some of the parts illustrated in Fig. 2, but showing the manually-con-

trolled means in operative position to permit the loom to be run without the shuttle. Fig. 4 is a detached plan view of the manually-controlled means detached; and Fig. 5 is an 5 enlarged transverse sectional detail on the line 5 5, Fig. 2, looking toward the right.

Referring to the drawings, the breast-beam A⁴⁰, lay A³, equipped with usual shuttle-boxes, one of which is indicated at B, Figs. 10 2 and 3, the protector mechanism, including a spring-controlled rock-shaft P, mounted on the lay, its upturned binder-fingers P', one for each binder P^X, the dagger P² to at times coöperate with the frog P³, Fig. 1, the shipper 15 N, its notched holding-plate N^X and the knock-off lever p³, Fig. 1, to release the shipper and stop the loom by or through engagement of the dagger with the frog may be and are all of well-known or usual construction 20 and operate in a manner familiar to those skilled in the art.

The loom is shown as equipped with filling-replenishing mechanism, including a filling feeder or hopper at F, Fig. 1, a transferrer f', 25 and a controlling rock-shaft d', all of which may be substantially as in United States Patent No. 677,607, dated July 2, 1901. So, too, the feeler-arm f^{2X} f^{3X}, fulcrumed at a' and provided with a wear-plate 90 and the feeler 30 proper, f^X, to intermittently pass through slots in the front wall of the shuttle-box B and shuttle to periodically engage and be moved by the filling in the shuttle until such filling is substantially exhausted, are substantially as shown in said patent.

The filling-fork m^X, its slide m, the weft-hammer W, having the usual hook to engage the tail of the fork and move the slide outward upon detection of failure of filling, (as 40 its breakage or a failure of the shuttle to thread upon filling replenishment,) and to operate the knock-off lever n' n², Fig. 2, to release the shipper, are all of usual construction.

An upturned arm d⁵, fast on the rock-shaft d', has pivotally connected with it the outer end of a latch d⁶, the rear end d⁷ of the latch being adapted to at times be engaged by a bunter w^X (see Fig. 5) on an upturned head w on the weft-hammer at one side of the guide for the weft-fork slide m, as in United States Patent No. 720,209. A projection w' on the head w coöperates intermittently with a cam-face d⁸ on the under edge of the latch, 55 Fig. 5, and the plate 90 is moved beneath an overhanging shoulder d⁹ on the latch by a spring 70, thus maintaining the latch end d⁷ in the path of the bunter w^X. Filling-induced movement of the feeler f^X withdraws 60 the plate and the latch end drops below the bunter path as the weft-hammer swings forward, and on its backward swing the projection w' engages the cam-face d⁸ and lifts the latch to permit the plate 90 to again pass under the shoulder d⁹, all as in Patent No. 720,209.

In Fig. 1 a portion of a multiple-harness

shedding mechanism is shown, comprising in the present instance ten leaves or harness-frames 1, 2, 3, to 10, suspended by overhead connections from the head or top motion H of any suitable construction, the particular form of dobby-head or top motion forming no part of the invention. The shedding mechanism is supposed to operate through a 75 cycle of a certain number of picks—ten as herein shown—and it is supposed that the pattern or weave is such that it is incumbent upon the weaver to match the pick upon filling failure. In order that the shuttle may 80 be removed and the loom run by power without hindrance to find the desired pick, the loom is provided with means to prevent operation of the protector mechanism in the first place and to prevent the filling-replenishing mechanism from operating in the second place. To this end a plate E, having longitudinal slots e^X, is slidably mounted on the top or cover plate b^X of the shuttle-box B, Figs. 2 and 3, and held in place thereon by 90 headed studs e' and washers 12, a spring s^X, secured to the outer end of the plate E and to the cover-plate, normally retaining said plate in inoperative position. (Shown in Fig. 2.) The inner end of the plate has a cam-face e², 95 which at its rear end terminates in a shoulder e³, (clearly shown in Figs. 2 and 4,) and the adjustable contact-stud p' on the binder-finger P' is shown as provided with an upturned extension p² in the path of movement of the cam-face e² when the latter is moved inward. A projection or handpiece e on the plate E facilitates its movement by the operator.

Supposing the loom to have been stopped, as by detection of filling failure, the weaver 105 moves the slide E inward into operative position, (shown in Fig. 3,) such movement bringing the cam-face e² into engagement with the binder-finger extension p² and pressing it back until it snaps behind the shoulder e³ 110 and then the plate is held in operative position. At the same time the part e⁴ of the plate adjacent the shoulder holds the extension back, with the binder-finger pressed back far enough to raise the point of the dagger P² well above the frog, so that the loom cannot "bang off." The operator now removes the shuttle and moves the shipper to running position and runs the loom carefully, but without any danger of banging off, until 120 the desired pick is reached, sometimes running the loom through practically a complete shedding cycle. The proper pick having been reached, the loom is stopped and the shuttle is placed in the proper shuttle-box, 125 its engagement with either binder pushing the latter out far enough to throw the extension p² back beyond the shoulder e³. Thereupon the plate E is released, and the contraction of the spring s^X restores it to normal 130 inoperative position, Fig. 2, and the loom can be started up in regular operation.

With feeler-controlled replenishing mechanism it is also necessary, when running

the loom without the shuttle, to prevent the operation of the replenishing mechanism, and for this purpose the plate E, near its outer end, is provided with an L-shaped extension 5 E', which crosses the shuttle-box and overhangs the front wall b thereof, Figs. 1, 2, and 3. From the extremity of the extension projects a bunter e⁵, shown as slightly downturned at its front edge, at e⁶, the normal 10 position of plate E causing the bunter to remain clear of the feeler f⁸ or any of its connected parts. When, however, the plate is moved inward to operative position, Fig. 3, as described, the bunter is brought opposite 15 the outer end of the feeler-arm f⁸, and when the lay beats up the downturned end e⁶ of the bunter engages the feeler-arm and moves it forward, withdrawing the plate 90 from the latch-shoulder d⁹, just as is the case with 20 filling-induced movement of the feeler. Consequently the loom may be run without the shuttle and the filling-replenishing mechanism cannot be operated at such time. As no 25 filling is laid when the loom is run without the shuttle, the take-up must be prevented from operating to take up the cloth, or thin places in the latter would be produced. Such control of the take-up can be effected in various ways, and one practical way is herein 30 shown, it being remembered that the weft-hammer operates on alternate picks. The only portion of the take-up mechanism shown 35 is a part of the take-up ratchet a⁸, its actuating-pawl a², detent-pawl e¹⁰, and let-back pawl f¹⁰, substantially as in United States Patent No. 643,284, dated February 13, 1900. An upturned arm d²⁰, loosely mounted on the rock-shaft d', is swung out by every forward 40 movement of the fork-slide m, and said arm d²⁰ has a depending extension d²¹ to engage a pin a¹⁰ on the pawl-carrier a' and disengage the take-up pawl and ratchet when the fork-slide is moved outward. As in the patent just referred to, when the pawl a² is disengaged from the ratchet a⁸ the pawl e¹⁰ is lifted 45 and the pawl f¹⁰ will permit the ratchet to let back as many teeth as may be necessary or advisable. If the pawl takes up one tooth of the ratchet on each beat of the lay, then 50 let-back would be for two teeth, owing to the operation of the fork-slide on alternate beats. If the loom be equipped with two forks, then take-up can be arrested on each pick in which 55 the filling is arrested, as provided for in United States Patent No. 727,014, for example.

From the foregoing description it will be manifest that when the weaver is running the loom without the shuttle to find or match 60 a pick he must manually retain the shipper in running position, for unless so retained the fork-slide would release it and stop the loom. He is thus obliged to watch the operation of the loom closely and carefully and 65 to stop the loom when the required pick is found.

Various changes or modifications may be made by those skilled in the art in the construction and details of arrangement of the various parts herein shown and described 70 without departing from the spirit and scope of the invention, one practical embodiment thereof being illustrated and explained herein.

Having fully described my invention, what 75 I claim as new, and desire to secure by Letters Patent, is—

1. In a loom, multiple-harness mechanism adapted to operate in a predetermined sequence, a shuttle to lay the filling, means, including a filling-fork, to stop the loom automatically upon filling failure, protector mechanism, and means movable manually into position to prevent the operation of said mechanism, whereby by removing the shuttle after 85 automatic stoppage of the loom the latter may be run to complete the shedding cycle and find the pick in which filling failure occurred.

2. In a loom, shed-forming mechanism adapted to operate in a recurring cycle of 90 three or more picks, a shuttle to lay the filling, means operative automatically by or through filling failure to stop the loom, protector mechanism, and means movable manually into position to arrest the operation thereof, whereby 95 upon removal of the shuttle after automatic stoppage of the loom the latter may be run to complete a shedding cycle and find the pick in which filling failure occurred.

3. In a loom, shed-forming mechanism 100 adapted to operate in a recurring cycle of three or more picks, a shuttle to lay the filling, means operative automatically by or through filling failure to stop the loom, protector mechanism, including a dagger and a frog, and 105 means movable manually into position to prevent co-operation of the dagger with the frog, whereby the shuttle may be removed and the loom run to complete a shedding cycle and find the pick in which filling failure occurred. 110

4. In a loom, shed-forming mechanism adapted to operate in a recurring cycle of 115 three or more picks, a shuttle to lay the filling, means operative automatically by or through filling failure to stop the loom, protector mechanism, including a dagger and a binder-finger, and means movable manually into engagement with and to retract the binder-finger and thereby render the dagger inoperative, whereby by removal of the shuttle the loom 120 may be run without hindrance to again present the pick of the shedding cycle in which filling failure occurred.

5. In a loom, shed-forming mechanism 125 adapted to operate in a recurring cycle of three or more picks, a shuttle to lay the filling, means operative automatically by or through filling failure to stop the loom, protector mechanism, a lay, and normally inoperative means mounted thereon and movable manually into 130 operative position to arrest the operation of the protector mechanism, whereby after stop-

page by filling failure the loom may be run without the shuttle to complete a shedding cycle and present the pick of the cycle in which filling failure occurred.

- 5 6. In a loom, shed-forming mechanism adapted to operate in a recurring cycle of three or more picks, a shuttle to lay the filling, means operative automatically by or through filling failure to stop the loom, protector mechanism, including a dagger and a binder-finger, a lay, and a retractor mounted thereon and movable manually into position to engage and retract the binder-finger and render the dagger inoperative, whereby by removal of the shuttle the loom may be run without hindrance to find the pick in which filling failure occurred, replacement of the shuttle thereafter releasing the binder-finger from the control of the retractor and rendering the protector mechanism again operative.

7. In a loom, a shuttle to contain filling, protector mechanism, including a dagger, and a frog, a lay, means mounted thereon and movable manually into position to prevent co-operation of the dagger and frog, whereby by removal of the shuttle the loom can be run without hindrance to find a pick in which filling failure occurred, replacement of the shuttle automatically releasing the protector mechanism from the control of said means, a device to automatically return said means to inoperative position, and means to stop the loom automatically by or through filling failure.

8. In a loom, shed-forming mechanism adapted to operate in a recurring cycle of three or more picks, a shuttle to lay the filling, means operative automatically by or through filling failure to stop the loom, protector mechanism, including a binder-finger and a dagger, a lay, and a spring-controlled device slidable thereon manually to retract the binder-finger and hold it retracted, thereby rendering the dagger inoperative, whereby by removal of the shuttle the loom may be run to complete a shedding cycle and find the pick in which filling failure occurred, replacement of the shuttle acting to release the binder-finger from control of said device and permitting the latter to return to inoperative position.

9. In a loom, a shuttle to contain a supply of filling, mechanism to cause automatically replenishment of the shuttle with filling or to effect the stoppage of the loom, shed-forming mechanism to operate in a recurring cycle of three or more picks, protector mechanism, and means movable manually into position to arrest the operation of the protector and prevent filling replenishing, whereby upon removal of the shuttle the loom may be run without hindrance to find any desired pick of the shedding cycle.

10. In a loom, shed-forming mechanism to operate in a recurring cycle of three or more picks, a shuttle to contain a supply of filling, automatic filling-replenishing mechanism op-

erative upon substantial exhaustion of the running filling, means to stop the loom by or through breakage of the filling, protector mechanism, and manually-controlled means to arrest the operation of the protector mechanism and prevent filling replenishment when the loom is run without the shuttle, whereby any desired pick of the shedding cycle may be readily found.

11. In a loom, shed-forming mechanism to operate in a recurring cycle of three or more picks, a shuttle to contain a supply of filling, automatic filling-replenishing mechanism, means, including a filling-feeler, to cause the operation thereof upon substantial exhaustion of the running filling, stopping means for the loom, operative upon breakage of the filling, protector mechanism, and manually-controlled means to prevent the operation of the protector mechanism and to co-operate with the feeler to prevent filling replenishment, whereby upon removal of the shuttle the loom may be run without hindrance to find any desired pick of the shedding cycle.

12. In a loom, shed-forming mechanism adapted to operate in a recurring cycle of three or more picks, a shuttle to lay the filling, means operative automatically by or through filling failure to stop the loom, protector mechanism, mechanism to replenish the shuttle with filling automatically upon substantial exhaustion of the filling therein, a lay, and means mounted thereon and movable manually into position to prevent the operation of the protector and filling-replenishing mechanisms, whereby upon removal of the shuttle after automatic stoppage of the loom the latter may be run to complete a shedding cycle and find the pick in which filling failure occurred.

13. In a loom, shed-forming mechanism adapted to operate in a recurring cycle of three or more picks, a shuttle to lay the filling, means operative automatically by or through filling failure to stop the loom, protector mechanism, including a shuttle-binder and a binder-finger, mechanism to replenish the shuttle with filling automatically upon substantial exhaustion of the filling therein, a lay, and means mounted thereon and movable manually into position to engage and hold out the binder-finger and prevent operation of the protector mechanism and also to prevent the operation of the replenishing mechanism, whereby upon removal of the shuttle the loom may be run without hindrance to find the pick in which filling failure occurred, subsequent engagement of the replaced shuttle with the binder releasing the binder-finger from said manually-movable means, and a spring to return the latter automatically to inoperative position.

14. In a loom, shed-forming mechanism adapted to operate in a recurring cycle of three or more picks, a shuttle to lay the filling, means operative automatically by or through filling failure to stop the loom, protector mech-

anism, take-up mechanism, means movable manually into operative position to arrest the 5 operation of the protector mechanism, where- by upon removal of the shuttle after auto- matic stoppage of the loom the latter may be run without hindrance to complete a shed- d¹⁰ing cycle and find the pick in which filling failure occurred, and means to prevent tak- ing up of the cloth when the loom is run with- out the shuttle.

15. In a loom provided with automatic fill- ing-replenishing mechanism, means, includ- ing a feeler to intermittently engage the fill- ing in the shuttle, to effect the operation of 15 said mechanism upon substantial exhaustion of the running filling, a shuttle to contain a supply of filling, protector mechanism, take- up mechanism, means manually movable into position to render the protector mechanism 20 inoperative and to prevent operation of the replenishing mechanism when the loom is run without the shuttle, and means to prevent taking up of the cloth when the loom is so run.

25. 16. In a loom provided with automatic fill- ing-replenishing mechanism, means, includ- ing a feeler to intermittently engage the fill-

ing in the shuttle, to effect the operation of 30 said mechanism upon substantial exhaustion of the running filling, a shuttle to contain a supply of filling, and means manually mov- able into operative position to prevent opera- 35 tion of the replenishing mechanism when the loom is run without the shuttle.

17. In a loom provided with automatic fill- 35 ing-replenishing mechanism, means, includ- ing a feeler to intermittently engage the fill- ing in the shuttle, to effect the operation of 40 said mechanism upon substantial exhaustion of the running filling, a shuttle to contain a supply of filling, protector mechanism, means manually movable into operative position to render the protector mechanism inoperative 45 and to prevent operation of the replenishing mechanism when the loom is run without the shuttle.

In testimony whereof I have signed my name to this specification in the presence of two subscribing witnesses.

DAVID ROBINSON.
